UPHOLSTERY SUPPORTING MEANS AND
METHOD OF USING THE SAME

Sydney Benmax, Chiswick, London, England

Application January 24, 1948, Serial No. 4,128
In Great Britain January 28, 1947

2 Claims. (Cl. 155—184)

1

This invention relates to the upholstering or covering of furniture and other articles in which upholstery and/or other covering material is attached to a supporting member.

I have previously proposed to provide a frame for an upholstered article of furniture, for example an easy chair or settee, having teeth, prongs or the like thereon stamped out of the material of the frame integral therewith for the attachment of upholstery material thereto, wherein the teeth point in the direction of application of the said material so that the tension in the material when applied to the frame tends to pull the material on to the teeth and prevent its release. After the upholstery material has been hooked over the teeth or the like, the latter may be pressed into or towards the plane of the frame out of which the teeth are struck to grip the upholstery material securely.

It is an object of the present invention to provide a supporting member, for example a furniture frame member, having an improved construction of teeth, prongs or the like thereon for the attachment thereto of upholstery and/or other material.

It is a further object of the invention to provide a furniture frame having an improved construction of teeth, prongs or the like thereon for the attachment thereto of upholstery and/or other covering material.

Thus according to the present invention there is provided a supporting member, for example a furniture frame member, having teeth, prongs or the like thereon, characterised by the fact that the teeth are formed so as to be able to secure two pieces of covering material to the frame member when said material is applied thereto with the tension in one piece acting in the opposite direction from the tension in the other piece.

More particularly in one form of the invention some or all of the teeth may be bent acutely back intermediate the tip and root thereof.

Further according to the invention there is provided a furniture frame comprising a toothed frame member as set forth above.

Teeth as set forth above may be readily formed integral with the material of a metal frame or other metal supporting member by stamping or striking out the teeth therefrom slightly out of the plane thereof and then, in the case of bent teeth, bending back the pointed end portions thereof at an acute angle.

Teeth thus formed serve the dual purpose of holding two different pieces of covering mate-

2

rial applied in opposite directions. In the case of bent teeth the tension in one material tends to draw the latter on to the base of the teeth, while the tension in the other material tends to draw said material towards the bend in the teeth. Frame members having teeth according to the present invention are particularly useful for fixing the upholstery and the under covering material to the underneath surface of the seat portion of a chair or settee.

The invention is illustrated by way of example in the accompanying drawings, in which:

Figure 1 is a perspective view from beneath of a chair with an upholstered seat according to one form of the invention;

Figure 2 is a perspective view on an enlarged scale of one of the teeth shown in Figure 1, for holding the covering material;

Figure 3 is a side view corresponding with Figure 2;

Figure 4 is a sectional side view corresponding with Figure 3 showing the manner in which two pieces of covering material are attached to a tooth;

Figure 5 is a sectional side view corresponding with Figures 3 and 4 showing a tooth holding the covering material; and

Figure 6 is a fragmentary perspective view of a modification of the construction of Figures 1 to 5.

In the construction shown in Figures 1 to 5 of the drawings, a chair generally indicated at 10 comprises a seat frame generally indicated at 11, the base of which includes four metal frame members 12 arranged substantially in the form of a square. Each frame member 12 may be of simple U-shape, L-shape or other section providing each frame member with a flat under surface, and each of said under surfaces is formed integrally, or otherwise, with downwardly projecting teeth, prongs or the like, generally indicated at 13. In the construction shown, the teeth are stamped out of the material of the frame member each tooth leaving an aperture 13c in the frame member. The central axes of the teeth are at right angles to the longitudinal axis of the member in which they are formed, the base of each tooth being disposed towards the outer edge of the frame member 12, and the teeth are bent sharply back at 13b as shown, out of the straight shape indicated by chain lines in Figure 3, so that the tip portions 13a of the teeth point slightly downwardly and outwardly.

A seat having the above construction of base 55 may be upholstered and under-covered as fol-

lows. The stuffing (or seat springs, not shown) is covered with upholstery material generally indicated at 14 providing a downwardly depending skirt 14a all round the seat. This skirt is drawn tightly underneath the toothed surface of the frame members 12 forming the seat base and on to the teeth 13 so that the latter pierce the upholstery which passes round the bend 13b in the teeth and is drawn tightly outwards by its own resiliency to the root of the teeth as shown. In this way, the upholstery 14 may be secured all round the seat.

The undersurface of the seat base is covered with canvas or other suitable material 15 by hooking the edge portions of the latter on to the teeth 13, the tension in the material 15 in this case resiliently pulling the material 15 towards the bend 13b in the teeth and holding it securely in position so that the edges of the upholstery material 14 previously applied are 20 covered. The teeth may be hammered or otherwise pressed towards or into the plane of the seat frame members 12 to complete the attachment.

Instead of providing a metal furniture or 25 other frame with teeth as indicated above, a supporting member 16, shown in Figure 6, such as a furniture frame, may be made of wood or other non-metallic material and have secured thereto a supporting member 17 provided with 30 metal teeth as described above.

It is to be understood that the invention is not limited to the particular construction described above.

What I claim is:

1. A method of covering a furniture frame comprising forming a a plurality of projections integrally with a metal upholstery member slightly out of the plane of the member and bending acutely back each of said projections 40 intermediate the tip and base thereof, applying two pieces of covering material in opposite directions in such a manner so that the tension

in one of said pieces tends to draw the latter on the base of the projections, while the tension in the other piece of the material tends to draw said other piece towards the bend in the projections, and pressing said projections into or towards the plane of the frame after the covering material has been applied.

2. A furniture frame comprising a metal upholstery member having a plurality of projections formed integrally therewith, each of said projections being disposed slightly out of the plane of said member and being bent acutely back intermediate the tip and the base thereof to provide oppositely inclined portions between said tip and the bend and between said base and the bend so that two pieces of covering material may be applied to said projections and tensioned in opposite directions so that the tension in one of the pieces tends to draw the latter onto the bases of said projections while the tension in the other of the pieces tends to draw that other piece toward the bends of said projections.

SYDNEY BENMAX.
